ADJUSTABLE FLOOR LAMP

Bernard Kotzin, Sr., Los Angeles, Calif.

Application August 30, 1954, Serial No. 32,074

Term of patent 14 years

(Cl. D48—20)

Fig. 1 is a perspective view of an adjustable floor lamp embodying my new design;

Fig. 2 is a side elevational view showing the lamp in extended position.

I claim:

The ornamental design for an adjustable floor lamp, substantially as shown.
